UNITED STATES PATENT OFFICE.

CARL CHRISTIAN, OF CLEBURNE, TEXAS.

LUNCH-BOX.

1,043,203.

Specification of Letters Patent.

Patented Nov. 5, 1912.

Application filed March 31, 1911. Serial No. 618,080.

To all whom it may concern:

Be it known that I, CARL CHRISTIAN, a citizen of the United States, residing at Cleburne, in the county of Johnson and 5 State of Texas, have invented certain new and useful Improvements in Lunch-Boxes, of which the following is a specification.

My invention relates to new and useful improvements in lunch boxes, and its object 10 is to provide a lunch box, having a novel and efficient means by which the cover may be securely fastened to the box.

The object of the invention is more specifically to provide a lunch box, having its 15 cover secured in place by a latch fastening, the walls of the box furnishing resiliency to hold the latch normally closed.

Finally the object of the invention is to 20 provide a lunch box, having a strong and durable construction, and adapted to protect its contents thoroughly against dust and dirt, or injury of any sort.

With these objects in view, my invention 25 has relation to certain novel features of the construction, an example of which is described in the following specification and illustrated in the accompanying drawing.

A perspective view of the lunch box is 30 shown in the drawing, the cover thereof being shown separate from the box to give additional clearness.

Referring now to the letters which are 35 employed on the drawing to designate the varicus parts, the letter A denotes the side or wall of the box, which will preferably have an oval form, and be made of light 40 springy wood. At one extremity of the box a post B is mounted upon the wall A, the lower portion of said post being bifurcated to receive said wall. The upper extremity of the post B projects slightly above the upper edge of the wall A, and is provided with a pair of oppositely disposed grooves C coincident with the upper edge of the wall 45 A, a neck D being formed between the two grooves. The other extremity of the box carries a similar post E, having its lower portion bifurcated to receive the wall A, and having its upper extremity projecting 50 slightly above the edge of the wall. A latch-head F is provided upon the inner face of the post E at its extremity.

The lunch box cover G, which is oval in

form to correspond with the shape of the lunch box is provided with grooves H at 55 each extremity, one of said grooves being adapted to receive the neck D of the post B, and the other to receive the post E beneath the latch-head F. In placing the cover upon the box, the neck D is first made to receive 60 one of said grooves in the cover. The other extremity of the cover is then forced down upon the beveled surface of the latch-head, and the resiliency of the wall A permits the latch-head to momentarily yield, permitting 65 the cover to pass down into contact with the rim of the box. The resiliency of the wall A will then throw the latch-head back to its normal position, locking the cover in place. In removing the cover the handle 70 thereof may be gripped with one hand, while the other hand is employed to release the latch F. After the extremity of the cover, adjacent to the latch-head, has been raised the other extremity may be readily 75 withdrawn from the neck D.

The construction above described is very durable, yet inexpensive, and the closure is one that may be readily fastened or removed, and affords secure protection to the 80 contents of the box.

All of the parts above specified will preferably be constructed of wood, but it is obvious that other suitable material may be used without departing from the spirit of the invention. It will also be apparent that the use to which the device may be applied is not limited to lunch boxes, but is applicable 85 to receptacles of various sorts.

What I claim is:

In a device of the character described, the combination with a receptacle, having a curved resilient wall, of posts oppositely mounted on said wall, one of which is provided with a neck, and the other with a 95 latch-head, and a closure having opposite grooves in its rim, said grooves being adapted to engage the two posts at the neck of one and beneath the latch-head of the other.

In testimony whereof I have signed my 100 name to this specification in the presence of two subscribing witnesses.

CARL CHRISTIAN.
